UNITED STATES PATENT OFFICE.

JAMES ROBERT OLIVER, OF DECATUR, ALABAMA.

SPRING-MOTOR.

SPECIFICATION forming part of Letters Patent No. 732,777, dated July 7, 1903.

Application filed February 20, 1903. Serial No. 144,254. (No model.)

To all whom it may concern:

Be it known that I, JAMES ROBERT OLIVER, a citizen of the United States, residing at Decatur, in the county of Morgan and State of Alabama, have invented a new and useful Spring-Motor for Sewing-Machines, of which the following is a specification.

My invention relates to spring-motors designed especially for sewing-machines, but susceptible of use with any form of machinery which may be operated in a substantially similar manner.

One object of the present invention is to improve the construction of motors of the class described by providing a very simple and inexpensive form of apparatus in which the number of parts is reduced to a minimum and the probability of wear diminished.

A further object of the invention is to provide a spring-motor adapted to be secured to the supporting-frame of the sewing-machine instead of to the table thereof, so adapting the motor to sewing-machines of the drop-head type.

25 A further object of the invention is to make it possible to wind the motor without stopping the machine and to make the control of the speed more convenient and positive in character than in any previous forms of motor.

The invention consists in the construction and novel arrangement and combination of parts of a spring-motor hereinafter fully described, illustrated in the accompanying drawings, and pointed out in the claims hereto appended.

In the drawings, Figure 1 is a front elevation of the sewing-machine with the improved form of spring-motor attached thereto, the 40 casing of the motor being removed to disclose the construction of the motor more clearly. Fig. 2 is a rear elevation of the machine with the motor attached. Fig. 3 is a vertical transverse section through the main shaft of the motor. Fig. 4 is a plan view of the motor in the supporting-frame of the machine, the table of the machine and the sewing-machine itself being removed. Fig. 5 is a detail view, on enlarged scale, of the ratchet mechan-

ism for controlling the direction of rotation 50 of the main shaft of the motor.

In all the figures corresponding parts are designated by the same characters of reference throughout.

1 indicates a main driving-wheel consisting 55 of a bevel-gear mounted on a horizontal shaft 2, which is arranged transversely of the sewing-machine frame and is supported in bearings provided on the members of said frame.

3 is a flat spring coiled upon the shaft 2 and 60 having one end fastened thereto from which power is transmitted to the main driving-wheel 1. The outer end of the spring 3 is fastened to a suitable lug or pin 4, provided on the rim of the main driving-wheel 1 and 65 projecting at right angles to its plane of rotation.

5 is a band-wheel of the ordinary type for driving the machine and is supported upon a short shaft 6, mounted on the frame of the 70 machine. Rigidly secured to the band-wheel 5 and adapted to rotate therewith on its shaft is a small bevel-gear 7, which is in mesh with the bevel-gear teeth on the main driving-wheel 1. By means of the bevel-gear 7 and 75 the bevel-gear on the main driving-wheel 1 motion is imparted to the band-wheel for driving the machine, and the driving of the machine is accomplished by means of the band 8, of usual form, which runs over the band-wheel and a pulley on the end of the main shaft of the machine proper. At the rear end of the shaft 2 is rigidly mounted thereon a large sprocket 11, and between the sprocket and the main driving-wheel a ratchet 12 is 80 rigidly secured to the shaft and adapted to engage with a spring-pressed pawl 13, mounted on the frame of the machine. At the right-hand side of the machine as viewed from the front a shaft 14, provided at its forward end 85 with a crank 15 and at its rear end with a small sprocket 16, is supported in bearings on the machine-frame at a convenient height to be operated by the user of the machine while the machine is in operation. Running over 90 the large sprocket 11 and the small sprocket 16 is a chain 17 of suitable form.

By means of the mechanism above de-

scribed power may be imparted to the machine as follows: By turning the crank 15 to the right the main shaft 2 is rotated through the chain and sprocket connections with the 5 shaft 14, and the spring 3 is wound up. As soon as the tension of the spring 3 becomes sufficiently strong the main driving-wheel 1 is set in motion, and by means of its bevel-gear connection with the band-wheel 5 motion 10 is imparted to the band-wheel and from it to the machine proper.

In the foregoing description of the construction of my improved spring-motor for sewing-machines no reference has been made to the 15 controlling mechanism whereby the motor is started, stopped, and its speed regulated. The preferred form of controlling mechanism is that illustrated in the drawings and comprising a pivoted arm 20, provided with 20 a brake-roll 21, rotatably mounted on an axle 22 and held in engagement with the band-wheel 5 by means of a spiral spring supported on a bracket just below the pivoted arm. The means for removing the brake from the 25 band-wheel consists of a pivoted foot-plate 23, connected with the brake-arm 20 by means of a link 19.

It will be readily understood on an inspection of the drawings that when no pressure 30 is applied to the foot-plate 23 the brake-roll 22 is pressed against the band-wheel 5 with sufficient force to prevent any rotation being imparted thereto by means of the driving-spring of the motor, and when it is desired 35 to set the motor in operation it is only necessary to remove the brake-roll from the band-wheel by pressing downward upon the foot-plate 23, which is so situated that it may be conveniently operated by the user of the machine without any material change of position.

The special advantages of a brake mechanism of this character as controlling means for a sewing-machine motor are that while the band-wheel may always be stopped or 45 started as quickly as may be desired and its speed kept completely under control the motion of the wheel will never be stopped so suddenly as to break the sewing-machine needle or to tear the fabric as it passes between the reciprocating feed-plate and the presser-foot of the machine.

In order to protect the working parts of the motor from dust and to keep their oiled surfaces from injuring fabrics accidentally 55 brought in contact therewith, I provide on the back of the main driving-wheel 1 a casting of sheet metal which entirely covers the spring on its rear side, and secured at the front and back of the motor are removable 60 shields of the form shown. The shields and casing for the spring may be fastened into position in any suitable manner; but it is preferable to fasten them to the frame members rather than to the machine-table and to

use bolts or other fastening devices which 65 may be readily disengaged to facilitate the removal of the shields and casing should it become necessary to adjust or clean the motor mechanism.

It will be readily understood from the foregoing description of the construction and arrangement of the parts of my spring-motor that only one hand is required to keep the motor wound and that the winding is necessary at intervals of considerable length only, 70 thus leaving one hand always free to control the feed of the fabric to the sewing-machine and during the most of the time permitting the use of two hands for feeding the fabric. It will also be understood that the winding 80 can be done without checking the movement of the machine, because the main drive-wheel 1 is freely rotatable upon its shaft 2 and is subject to a forward impulse from the spring 3 just as long as the spring is under any tension. 85 Owing to the convenient location of the controlling-brake and its operating mechanism, the speed of the machine is always easily controlled by means of the foot. By using the sprocket-and-chain connection between the 90 winding-shaft 15 and the main driving-shaft 2 instead of the train of gears employed in my former patent, No. 657,318, I obtain a winding mechanism of very durable and inexpensive form, which is more satisfactory in operation. 95

Having now fully described the construction and operation of my improved spring-motor for sewing-machines, what I claim as my invention, and desire to secure by Letters Patent, is—

1. The combination with a machine-frame of a spring-motor having a main driving-shaft arranged horizontally and transversely of the machine-frame, a main driving-wheel loosely mounted on said shaft and having 105 bevel-teeth at its periphery, a band-wheel rotatably mounted on a shaft supported upon the frame and disposed at right angles to the main driving-shaft of the motor, said band-wheel having bevel-teeth provided on its hub 110 to mesh with bevel-teeth on the main driving-wheel, a belt-receiving groove on its periphery and a flange projecting laterally from its periphery, a brake comprising a pivoted arm and a braking member mounted on the main 115 frame and held normally in engagement with said flange, a driving-spring coiled on the main driving-shaft and having one end secured to said shaft and one end secured to said main driving-wheel, a pawl-and-ratchet 120 mechanism for controlling the direction of rotation of said main shaft, and winding mechanism for said main shaft.

2. The combination with a machine-frame of a band-wheel rotatably mounted on a shaft supported on said frame and having a flange projecting laterally from one face thereof, a spring-motor directly connected with said 125

band-wheel, a brake mechanism for controlling the movements of said band-wheel, said brake mechanism comprising a pivoted arm mounted on said main frame beneath the 5 band-wheel, a bracket beneath said brake-arm, a spring on said bracket engaging said arm, a roller carried by said arm and held normally in engagement with said flange, a pivoted foot-plate at the bottom of said flange,

and a link connecting said foot-plate and said 10 arm.

In testimony that I claim the foregoing as my own I have hereto affixed my signature in the presence of two witnesses.

JAMES ROBERT OLIVER.
